TOOTH BRUSH

Ralph L. Tweedale, Detroit, Mich.

Application February 26, 1931, Serial No. 518,546
Renewed October 17, 1938

19 Claims. (Cl. 15—176)

This invention relates to tooth brushes of the type in which the brush part is removable so that it can be replaced by a refill in order to make it possible to frequently discard the used brush part without undue expense to the user.

More particularly the invention relates to tooth brushes of the above type in which the refill is provided with a protective wrapping preferably of a tough transparent material such as that known on the market as Cellophane and in which or in connection with which means is provided for severing the wrapping as the refill is about to be used. It becomes rather difficult to break open a wrapping of ordinary Cellophane when the package wrapped is small such as a tooth brush refill as contemplated by this invention. It is therefore one object of the present invention to provide means for easily severing such a wrapping.

Other objects of the invention are to provide an improved means to hold a tooth brush refill, to provide such a means in which there is a provision for severing the wrapping, to provide an improved refill which will be attractive, convenient, and sanitary and one which will include everything necessary to the user for brushing his teeth.

Four embodiments of the invention are illustrated in the accompanying drawing in which Fig. 1 is a side view of a tooth brush embodying the invention;

Fig. 2 is a cross-section on line 2—2 of Fig. 1;

Fig. 3 is a cross-section on line 3—3 of Fig. 2 showing the refill before insertion;

Fig. 4 is a side view of a tooth brush embodying a second form of the invention;

Fig. 5 is a cross-section on line 5—5 of Fig. 6 showing the holder with a refill in position;

Fig. 6 is a cross-section on line 6—6 of Fig. 5 showing the refill before insertion;

Fig. 7 is a cross-section on line 7—7 of Fig. 9 of a refill dispenser embodying a third form of the invention;

Fig. 8 is a cross-section on line 8—8 of Fig. 7;

Fig. 9 is a side view of the dispenser shown in Fig. 7;

Fig. 10 is front view of cutter embodying a fourth form of the invention, and

Fig. 11 is a top view of the cutter shown in Fig. 10.

In the embodiment of invention shown in Figs. 1, 2, and 3 a tooth brush is provided which consists of a holder 1 having a handle part 2. The holder 1 is adapted to hold a refill 3 which consists of a back 4, bristles 5, a charge of dentifrice

6 and a wrapping 7 of a tough resilient material such as Cellophane. The wrapping 7 is hermetically sealed preferably by adhesion to the edges of the back 4 although it may be sealed in other ways such as by adhesion to the bottom 5 of the back or by folding and sealing the folds upon each other. The wrapping 7 is ordinarily rather difficult to open with the fingers only, so there is provided means to open the wrapping as it is secured in place.

The holder 1 has a recess 8 defined by the walls 9, 10, 11, and 12 and by the bottom 13 the latter forming a bridge member between the walls. The recess 8 is of slightly less depth than the thickness of the back 4 so that when a refill is placed 15 in recess 8 its back will project slightly above the top edge of the recess as shown in Fig. 2. A cutting edge 14 is provided at the top of wall 10. This cutting edge is located to come just even with the top of recess 8 and just below the top 20 of the back of the refill when in place. The end of holder 1 around the recess 8 is reduced in size to receive a cutting and retaining slide 15. The slide 15 has oppositely disposed members 16 having cutting edges 17 spaced apart by slightly less 25 than the width of the back 4 so that they will cut the wrapping 7 and tightly grip the back 4. A cutting edge 18 is provided at the end of the slide 15 opposite to the cutting edge 14. The slide 15 when in the position shown in Fig. 3 leaves the 30 recess 8 open to receive the refill 3, the recess being a little bit longer and wider than the back 4.

In operation the tooth brush is refilled by pulling slide 15 out to the position of Fig. 3, taking out the old refill element, placing the new one in the recess 8, and pushing slide 15 in to the position shown in Fig. 1. As slide 15 is pushed in the cutting edges 17 sever the sides of the wrapping 7 and grip the sides of the back 4. As the 35 slide is pushed home the cutting edges 14 and 18 cut the ends of the wrapping and grip the ends of the back. The wrapping is then lifted off and the tooth brush is ready for use. A lug 19 engages a recess 20 in the slide 15 to frictionally 40 hold it in the position of Fig. 1.

In the modification illustrated in Figs. 4, 5, and 6 a holder 21 has a handle part 22 and is adapted to hold a refill 23 similar to the refill 3 previously described. The end of holder 21 has 50 a recess 24 defined by the curved walls 24 and 25 and open at the end 26. Opposed members 27 overlap the top edges of the recess 24 and have cutting edges 28 located so as to just overlap the top edges of the back of a refill when positioned 55

in the recess. At the closed end of the recess is located the cutting edge 31. The opposite end 26 of the recess may be closed by a closure member 32 pivoted to the holder 21 at 33. The member 32 carries a cutting edge 34 located so that when the member 32 is in the position of Fig. 4 the edges 31 and 34 will just overlap the two ends of the refill when positioned in the recess. A lug 35 fits into a mating recess 36 to frictionally hold member 32 in the position of Fig. 4.

The operation of this modification is as follows: Member 32 is moved to the position of Fig. 6 and the old refill is removed by sliding it out the end 26. The fresh refill is then pushed in from end 26 in the direction of the arrow in Fig. 6. During this movement the overlapping edges 28 cut the wrapping by a shearing action between edges 28 and the back of the refill. As the refill is slid home edge 31 severs the end of the wrapping. Member 32 is then swung into the position of Fig. 4 and edge 34 at the same time severs its end of the wrapping. The tooth brush is now ready for use.

In the device of Figs. 7, 8, and 9 a container 37 is adapted to hold a plurality of refills 38 which may be similar to the refill 3. The refills normally rest upon a plunger 39. The plunger 39 is a little larger in cross-section than the refills 38 and is adapted to slide out to the dotted line position shown in Fig. 7. Opposite the left end of plunger 39 is an opening in the container 37 defined by the walls 40, 41, 42, and 43. The two opposite side walls 40 and 42 have cutting edges 44 adapted to sever the wrapping of a refill as it is pushed through the opening. A handle 45 is provided on plunger 39 which may be symmetrical in shape with the protuberance 46 in which the opening is located. A pin 47 on the back of plunger 39 slides in a slot 48 in the back wall 40 of the container 37 and limits the outward motion of plunger 39.

In operation of this modification the plunger 39 is withdrawn to the dotted line position which allows the refills above it to fall by gravity to the bottom of the container. The plunger is then pushed in to the full line position and at the same time the bottom refill is forced through the opening. This action cuts the sides of the wrapping by engagement with the cutting edges 44. The refill may then be withdrawn and the wrapping removed with the fingers.

In the modification of Figs. 10 and 11 a cutter 49 is provided having opposed cutting edges 50 overlapping a channel 51 shaped to correspond to the shape of the back of a refill. A support 52 is provided for the cutter 49 which is adapted for fastening to a convenient wall by screws 53. Tooth brush racks 54 are provided making the device capable of holding tooth brushes when not in use. In operation a refill is inserted at the top of the cutter with its back engaged in the channel 51. By forcing the refill through the channel the sides of the wrapping are severed by the shearing action between the cutting edges 50 and the back of the refill.

I claim:

1. A holder for a tooth cleaning appliance refill having a wrapping comprising means defining a recess for receiving a part of the refill, and means for cutting the wrapping which operates to sever the wrapping as the refill is secured in place in the holder.

2. A holder for a tooth brush refill having a wrapping, comprising a relatively long slender handle adapted to be readily grasped in the

hand, and means for cutting the wrapping of the refill and for holding the refill in position for use whereby the wrapper is severed as the refill is secured in position in the handle.

3. A holder for a tooth brush refill having a wrapping, comprising a relatively long slender handle adapted to be readily grasped in the hand, and means for cutting the wrapping of the refill and for holding the refill in position for use whereby the wrapping is severed as the refill is secured in position in the handle, at least part of the last named means being pivoted to swing into and out of refill securing position.

4. A holder for a tooth brush refill having a wrapping, comprising a relatively long slender handle adapted to be readily grasped in the hand, and means for cutting the wrapping of the refill and for holding the refill in position for use whereby the wrapping is severed as the refill is secured in position in the handle, at least part of the last named means operating by relative sliding motion between the refill and the means.

5. A refillable tooth brush comprising a holder having a handle part, a refill having a comparatively rigid back means on the holder for securing the refill in place in the holder said means acting to secure the refill in place by relative sliding motion longitudinally of the handle between the refill and the means and a detent for retaining the securing means in refill securing position.

6. A holder for a tooth brush refill, said refill having a flat comparatively rigid back and a wrapping, comprising means forming cutting and holding edges overlapping the back of the refill when in position whereby the wrapping is severed as the refill is slid into position and secured there.

7. A dispenser for packages containing tooth brush refills comprising a container for receiving a supply of packages under an urge to move to one end thereof, means defining an opening in one side of the container adjacent the said end, a member arranged for sliding movement toward and away from the opening and cutting edges arranged at the opening whereby the member may be operated to force a package through the opening and between the cutting edges for dispensing a package and at the same time severing its wrapping.

8. Means for opening a package containing a tooth brush refill having a back of comparatively rigid thick sheet material and a wrapping of tough thin sheet material overlying the edge of the back, comprising a cutter having walls defining an opening corresponding in size and shape to the size and shape of the back of the refill in cross-section, a cutting edge associated with one of the walls of the opening for severing the wrapping of the refill at the point where it overlies the back as it is passed through the opening and means forming a supporting structure for the cutter.

9. Means for opening a package containing a tooth brush refill having a back of comparatively rigid thick sheet material and a wrapping of tough thin sheet material overlying the edge of the back, comprising a cutter having walls defining an opening corresponding in size and shape to the size and shape of the back of the refill in cross-section, a cutting edge associated with one of the walls of the opening for severing the wrapping of the refill at the point where it overlies the back as it is passed through the open-

- ing and an article for toilette use forming a supporting structure for the cutter.
10. In a means for opening a package containing a refill for a tooth brush, said refill comprising a flat back of comparatively rigid material and a plurality of tufts of bristles set perpendicularly therein, said refill having a wrapping of tough flexible sheet material; the combination of a cutter supporting element, a member having a cutting edge adapted to coat with one side of said refill back to cut the wrapping at a point between the cutting edge and the back, a second member adapted to coat with the opposite side of said refill back to maintain the back in close engagement with the first member, and a bridge member connecting the first and second members and defining an opening to receive at least part of said refill back.
11. A tooth cleaning appliance comprising in combination a handle element and a refill element, the refill element including a thin comparatively rigid portion forming a back, a flexible portion adapted to engage the teeth for cleaning, a charge of dentifrice associated with the flexible portion and a hermetically sealed wrapping covering the refill and positioned adjacent the edges of the back, the handle element including a relatively long, slender portion adapted to be readily grasped in the hand and a refill securing portion which includes means for severing the wrapping of the refill when the refill is secured in position on the handle element.
12. A tooth cleaning appliance comprising in combination a handle element and a refill element, the refill element including a thin comparatively rigid portion forming a back, a flexible portion adapted to engage the teeth for cleaning, and a hermetically sealed wrapping covering the refill and positioned adjacent the edges of the back, the handle element including a relatively long, slender portion adapted to be readily grasped in the hand and a refill securing portion which includes means for severing the wrapping of the refill when the refill is secured in position on the handle element.
13. A tooth cleaning appliance comprising in combination a handle element and a refill element, the refill element including a thin comparatively rigid portion forming a back, a flexible portion adapted to engage the teeth for cleaning, a charge of dentifrice associated with the flexible portion and a hermetically sealed wrapping entirely surrounding the refill, the handle element including a relatively long, slender portion adapted to be readily grasped in the hand and a refill securing portion which includes means for severing the wrapping of the refill when the refill is secured in position on the handle element.
14. A device for opening a refill element for a tooth cleaning appliance, said refill element including a thin comparatively rigid portion forming a back, a flexible portion adapted to engage the teeth for cleaning, and a hermetically sealed wrapping of tough sheet material covering the refill and overlying the edges of the back, said device being formed with a flat bottom por-

tion to engage the bottom of the refill back, upright walls at the terminations of said bottom portion adapted to surround the edges of the refill back, and cutting edges associated with said upright walls and adapted to coat with the back 5 to sever the wrapping as the cutting edges and refill are moved relative to each other.

15. A refill element for a tooth cleaning appliance comprising in combination, a thin comparatively rigid back, a flexible portion adapted 10 to engage the teeth for cleaning, a charge of dentifrice associated with the flexible portion, and a wrapping of tough, flexible, sheet material completely covering the flexible portion and charge of dentifrice said wrapping overlying 15 the edges of the back and being hermetically sealed to maintain the flexible portion and charge of dentifrice in a sanitary condition.

16. A dispenser for tooth cleaning appliance refills, said refills including a thin comparatively 20 rigid portion forming a back, a flexible portion adapted to engage the teeth for cleaning, and a hermetically sealed wrapping of tough sheet material overlying the edges of the back and covering the refill, said dispenser including 25 means forming an opening through which refills may be dispensed said opening being formed with a flat bottom portion to engage the bottom of the refill back, upright walls at the terminations of said bottom portion adapted to surround the 30 edges of the refill back, and cutting edges associated with the upright walls and adapted to coat with the back to sever the wrapping as the refill is moved through said opening when dispensed.

17. A refill element for a tooth cleaning appliance comprising in combination, a thin comparatively rigid back, a flexible portion adapted 40 to engage the teeth for cleaning, a charge of dentifrice associated with the flexible portion, and a wrapping of tough, flexible, sheet material completely covering the flexible portion and charge of dentifrice, said wrapping being hermetically sealed to the back to maintain the flexible portion and charge of dentifrice in a 45 sanitary condition.

18. A refill element for a tooth cleaning appliance comprising in combination a thin comparatively rigid back, a flexible portion adapted 50 to engage the teeth for cleaning, a charge of dentifrice associated with the flexible portion, and a wrapping of tough, flexible sheet material completely covering the flexible portion and charge of dentifrice, said wrapping being hermetically sealed to maintain the flexible portion 55 and charge of dentifrice in a sanitary condition.

19. A refill element for a tooth cleaning appliance comprising in combination, a thin comparatively rigid back, a flexible portion adapted 60 to engage the teeth for cleaning, and a wrapping of tough flexible sheet material completely overlying the flexible portion and being hermetically sealed to maintain the flexible portion in a sanitary condition.
